UNITED STATES PATENT OFFICE.

JACOB GOERING, OF NEW YORK, N. Y.

HOT-WATER BOILER.

SPECIFICATION forming part of Letters Patent No. 332,147, dated December 8, 1885.

Application filed February 12, 1885. Serial No. 155,717. (No model.)

To all whom it may concern:

Be it known that I, JACOB GOERING, a citizen of the United States, residing at New York, in the county and State of New York, 5 have invented new and useful Improvements in Hot-Water Boilers, of which the following is a specification.

My invention relates to improvements in hot-water boilers; and it consists in the combination, with a hot-water boiler and the hot-water pipe, of a branched cold-water supply-pipe, one branch leading into the boiler and the other branch connecting with the hot-water pipe, a check-valve which is situated in 10 the branch leading to the boiler and opens inwardly, and a relief-valve situated in the branch leading to the hot-water pipe and opening outwardly.

In the accompanying drawings, Figure 1 is 20 a vertical longitudinal section of the improved hot-water boiler. Fig. 2 is a front view of a modification. Fig. 3 is a sectional view of a modification of the cold-water-supply pipe.

Similar letters indicate corresponding parts. 25 In the drawings, referring especially to Fig. 1, the letter A designates a hot-water boiler of ordinary construction, which is connected at its bottom head, a', with a water-back, B, by the pipes a and b, and some distance from 30 its bottom it is connected with the water-back by a bent pipe, c. C is the cold-water-supply pipe or water-main, which branches at d, one branch, e, leading through the top head, f, of the boiler to near the bottom of the same, and the other branch, g, connecting with the 35 hot-water pipe h, which leads from the top head, f, of the boiler. In the branch e is placed a check-valve, D, which opens inwardly, and the object of which is to prevent 40 the hot water in the boiler from backing out through the siphon-shaped branch e when the pressure in the main is diminished from some cause. In the branch g is placed a check or relief valve, E, which opens outwardly, and 45 allows the escape of the steam and water when the pressure of the boiler exceeds the proper limit—that is to say, when it exceeds the

pressure of the water in the main. It is evident that the relief-valve E is kept constantly closed by the pressure of the water in the cold-water-supply pipe C until, as before stated, the pressure in the boiler exceeds said pressure.

Instead of having the branch at d, a box may be used in which the two valves are placed, and the pipes e and g connected in their proper positions with said box, and also the supply-pipe may branch at any point in its length or directly at the water-main, as seen in Fig. 3.

In Fig. 2 the valves D E are shown in their respective positions when the cold water is fed in through the bottom head of the boiler. By the branching of the cold-water-supply pipe and the introduction of the check and relief valves in said branches, as described, there is no possibility of an excess of pressure arising in the boiler, which frequently causes the water-back to be blown out with the usual damaging effect; nor can the hot water in the boiler be siphoned out through the pipe e on an existing low pressure in the water main or supply.

What I claim as new, and desire to secure by Letters Patent, is—

The combination, with an upright hot-water boiler having a hot-water pipe rising from its upper head, of a single cold-water pipe having two branches at its upper end, one of which communicates with the interior of the boiler, adjacent to the lower head thereof, and the other of which connects with the hot-water pipe above the boiler, an upwardly-opening check-valve in the branch communicating with the boiler, and a downwardly-opening relief-valve in the other branch, substantially as described.

In testimony whereof I have hereunto set my hand and seal in the presence of two subscribing witnesses.

JACOB GOERING. [L. S.]
